RAILWAY TRAFFIC CONTROLLING APPARATUS

Arthur L. Jerome, Edgewood, Pa., assignor to The Union Switch & Signal Company, Swissvale, Pa., a corporation of Pennsylvania

Application June 17, 1943, Serial No. 491,114

15 Claims. (Cl. 246—47)

My invention relates to railway traffic controlling apparatus and more particularly to trackway apparatus for governing automatic train control devices.

Railway signal systems frequently employ train control or train stop apparatus, the trackway elements of which are controlled to a clear or a stop position in accordance with traffic conditions and which cooperate with train carried elements for controlling train carried apparatus in accordance with the condition of the trackway element. When a train is to move in the direction reverse to the normal direction of traffic, means must be provided to insure that the train control trackway elements assume an inoperative condition.

One object of my invention is the provision of railway traffic controlling apparatus incorporating improved directional means to insure movement of train control trackway devices to an inoperative position when a train is moving over the associated stretch of track in the reverse of the normal direction of traffic.

A further object of the invention is to provide improved apparatus of the type described which is arranged so that control of the trackway train stops on movement of a train through the track stretch in the reverse direction is effected without the use of apparatus other than that which is required for the control of these devices and of the wayside signals on movement of a train through the track stretch in the normal direction.

Other objects of the invention and features of novelty will be apparent from the following description taken in connection with the accompanying drawing.

I shall describe one form of apparatus embodying my invention and shall then point out the novel features thereof in claims.

In the drawing the single figure is a diagram of a stretch of railway track equipped with apparatus embodying my invention when used with automatic train stops of the trip-arm type for a two-block three-indication signal system.

In practicing my invention I employ a home relay governed by traffic conditions in a track section, and a distant relay governed by the home relay and by traffic conditions in advance. These relays govern the wayside signal for the section, while the home relay controls the associated trackway device on movement of traffic through the track stretch in the normal direction. On movement of a train through the track stretch in the reverse direction the distant relay serves

as a directional stick relay and establishes a circuit to cause the associated trackway device to permit the train to pass over the device.

Referring to the drawing, there is shown

5 therein a stretch of railway track through which traffic normally moves in the direction indicated by the arrow, that is from left to right. The track rails 1 and 2 of the track stretch are divided by insulated joints 3 into a plurality of 10 track sections designated 10T, 11T, 12T and 13T. Each of these track sections is provided with a track circuit of any appropriate form, the track relay of each track circuit being designated TR with an appropriate prefix.

15 Each track section has at the entrance end thereof a wayside signal designated S with an appropriate prefix. As shown these signals are of the color light type, and each has a green or clear lamp G, a yellow or caution lamp Y, and a red or stop lamp R. As hereinafter explained, these signals, except signal 13S for section 13T, are controlled to provide a two-block three-indication signaling system having a full block overlap. As illustrated in the drawing the signal

20 13S includes a green lamp G which may be employed to indicate traffic conditions in advance of section 13T. The circuit of lamp G of signal 13S may be controlled by appropriate means well known in the art, but the control of this lamp is not a part of this invention and has been omitted in order to simplify this disclosure.

25 The track section 13T at the right-hand end of the stretch is provided with an additional signal 13SL which is located at the right-hand end of the section and governs entrance into the track stretch of trains moving in the reverse of the normal direction. As shown the signal 13SL is a two position signal provided with lamps Y and R which are controlled over circuits including a contact 32 which is operated by a lever K which may form a part of an interlocking machine.

30 Each track section has associated therewith a trackway train stop device designated V with an appropriate prefix. These devices may be of any well known construction and are shown diagrammatically for simplicity. It is contemplated that these devices be of a trip-arm type, and they may be of the pneumatically operated electrically controlled construction wherein a trip-arm is biased by gravity or by springs, or both, to a raised or operative position, and is pneumatically moved to a lowered or inoperative position when a winding associated with the device is energized.

Each train stop V is located just to the rear of the entrance end of the associated track section and is situated on one side of the track for its trip-arm to cooperate with a train carried arm, the arrangement being such that when the trip-arm is in its raised or operative position it will engage the arm on a train to operate a control device on the train, as for example to apply the brakes on the train, and when the trip-arm is in its lower or inoperative position it is out of the path of the train carried arm.

Each train stop device has associated therewith contacts 18, 19 and 24 which are governed in accordance with the position of the arm of the device. The contacts 18 are controlled so as to be closed when and only when the associated trip-arm is in its lower or inoperative position, while each contact 19 is closed in all positions of the associated trip-arm except its lower or inoperative position, and each contact 24 is closed in all positions of the associated trip-arm except its raised or operative position.

Each track section is provided with a home relay designated H with an appropriate prefix, and a distant relay designated D with an appropriate prefix. The home relays H are of a type the contacts of which are slow to release. The relays H and D are controlled by the track relays and cooperate to control the wayside signals and the train stop devices in the manner hereinafter explained in detail.

The energy for operating the equipment other than the track relays is supplied from an appropriate source, not shown, the terminals of which are designated B and C in the drawing. Separate sources of energy may be provided at each signal location, in which event the common terminal C of the sources at various locations may be connected together by a common wire, not shown, or energy from a single source may be distributed throughout the track stretch by a transmission line, not shown.

The equipment is shown in the condition which it assumes when the track stretch is vacant and the lever K is in its position N in which it conditions the track stretch for movement of traffic in the normal direction.

As lever K is in its position N the lever contact 32 establishes the circuit of the red lamp R of signal 13SL to prevent entrance into the track stretch of trains moving in the reverse of the normal direction, while contact 34 establishes the circuit including front contact 38 of track relay 13TR for supplying energy to relay 13H, and interrupts the pick-up circuit of relay 13D. Accordingly, relay 13H is picked up and its contact 28 additionally interrupts the circuit of relay 13D, while energy is supplied to the winding of trip stop 13V over the circuit which includes front contact 20 of relay 13TR, front contact 21 of relay 13H, and wire 22, and the arm of the trip stop 13V is held in its lower or inoperative position so that contacts 18 and 24 are closed and contact 19 is open. As contact 30 of relay 13H is picked up, and as contact 19 of the trip stop is open, the supply of energy to the red lamp R of signal 13S is cut off, while energy is supplied over front contact 30 of relay 13H and trip contact 18 to the yellow lamp Y of signal 13S.

As section 12T is vacant track relay 12TR is picked up and its contact 26 establishes the circuit of relay 12D and energy is supplied to this relay over the circuit which includes front contact 20 of relay 13TR, front contact 21 of relay

13H, wire 22, trip contact 24, wire 25, and front contact 26 of relay 12TR.

As sections 12T and 13T are vacant energy is supplied over front contact 37 of track relay 13TR and front contact 38 of track relay 12TR to relay 12H so that its contacts are picked up so that energy is supplied over front contact 20 of relay 12TR, front contact 21 of relay 12H and wire 22 to the winding of trip stop 12V. The trip-arm of the device 12V, therefore, occupies its lower or non-tripping position and contacts 18 and 24 are closed, while contact 19 is open.

As relays 12TR, 12H and 12D are picked up energy is supplied to the green lamp G of signal 12S over front contact 40 of relay 12TR, front contact 39 of relay 12H, trip contact 18, and front contact 41 of relay 12D.

At this time energy is supplied to relay 11D over front contact 20 of relay 12TR, front contact 21 of relay 12H, wire 22, trip contact 24, wire 25, and front contact 26 of track relay 11TR.

The equipment associated with signal 11S is identical with that associated with signal 12S, and at this time operates in the same manner as explained in detail in connection with signal 12S to cause signal 11S to provide its green or clear indication, to cause the arm of trip stop 11V to occupy its lower or non-tripping position, and to cause energy to be supplied to the distant relay for section 10T.

Operation of system on movement of a train through the stretch in the normal direction of traffic

When a train moving in the normal direction of traffic enters section 10T the track relay, not shown, for section 10T releases and its contact 26 (similar to contact 26 of relay 11TR) connects wire 25 to terminal B of the source and thus establishes a stick circuit for trip stop 11V. This circuit includes wire 25 for section 10T, contact 24 of trip 11V, and wire 22, and provides means for maintaining the arm of the trip stop 11V in its lower or inoperative position when the train enters section 11T so that track relay 11TR releases and its contact 20 interrupts the circuit controlled thereby for supplying energy to the winding of this trip stop.

When the train enters section 11T and relay 11TR releases its contact 26 interrupts the circuit of relay 11D and establishes a stick circuit for trip stop 12V, while contact 40 of relay 11TR interrupts the circuit of the green lamp G and establishes the circuit of the red lamp R of signal 11S. In addition, contact 38 of relay 11TR interrupts the circuit of relay 11H, but the contacts of relay 11H are slow in releasing so contact 28 of relay 11H remains picked up and interrupts the stick circuit of relay 11D until after the contacts of relay 11D release. This insures that contact 27 of relay 11D will interrupt the stick circuit for the relay before it can be established by contact 28 of relay 11H, and therefore insures that the contacts of relay 11D will be released at this time so that contact 35 of relay 11D interrupts the circuit which it controls for supplying energy to the winding of the trip stop 11V.

When the train vacates section 10T the track relay for that section picks up and its contact 26 interrupts the circuit of the winding of trip stop 11V and the trip-arm of this device moves to its upper or operative position, while contact 24 is opened to interrupt the circuit of the trip device winding and to also interrupt the circuit

for supplying energy to the distant relay for section 10T.

When the train enters section 12T track relay 12TR releases and its contact 26 interrupts the circuit of relay 12D and establishes a circuit to supply energy to trip 13V, while contact 40 of relay 12TR interrupts the circuit of the green light G and establishes the circuit of the red lamp R of signal 12S. On release of track relay 12TR its contact 37 additionally interrupts the circuit of relay 11H, while its contact 38 interrupts the circuit of relay 12H and its contact 20 interrupts one circuit for supplying energy to the winding of the trip stop 12V. However, as long as a portion of the train remains in section 11T the winding of trip stop 12V is energized by current supplied over back contact 26 of relay 11TR so that the arm of trip stop 12V remains in its lower or inoperative position to permit the train to advance over the top. When the train vacates section 11T, the contacts of track relay 11TR pick up and contact 26 interrupts the supply of energy to the winding of the trip stop 12V and the arm of this device moves to its upper or tripping position to prevent movement of a second train over the device.

When the train vacates section 11T the circuit of relay 11H continues to be interrupted by contact 37 of relay 12TR so that relay 11H remains released and its back contact 30 establishes the circuit of the red lamp R of signal 11S, while its contact 21 interrupts the circuit controlled by front contact 20 of relay 11TR for supplying energy to the winding of trip 11V.

When the train enters section 13T the signals 13S and the trip stop 13V are affected in a manner similar to that just explained in connection with the signal 12S and trip stop 12V.

When the train vacates section 12T track relay 12TR picks up and its contact 37 establishes the circuit of relay 11H so that contact 21 of relay 11H completes the circuit including front contact 20 of relay 11TR for supplying energy to the winding of trip stop 11V. Accordingly, the arm of this device moves to its lower or non-tripping position and contact 24 establishes the circuit for supplying energy to the distant relay for section 10D.

When relay 11H picks up, its contact 30 interrupts one circuit for supplying energy to the red lamp R of signal 11S, and establishes the circuit including contact 19 of trip device 11W to maintain the red lamp R of signal 11S lighted until the arm of the trip device 11W completes its movement to its lower or non-tripping position. The corresponding contacts 19 at other locations in the stretch serve to maintain the display of a red or stop indication by the signal at that location during movement of the arm of the associated trip stop device from its upper or tripping position to its lower or non-tripping position. When the arm of the trip stop device 11W reaches its lower or non-tripping position, contact 19 interrupts a circuit for the red lamp of signal 11S, and contact 18 establishes the circuit including front contact 40 of relay 11TR, front contact 30 of relay 11H, trip contact 18, and back contact 41 of relay 11D for supplying energy to the yellow lamp Y of signal 11S.

Similarly, when the train vacates section 13T relay 12H picks up and the arm of trip device 12V moves to its lower or non-tripping position, and signal 12S displays its yellow or caution indication, while contact 24 of trip 12V establishes the circuit to supply energy to relay 11D so that

signal 11S displays its green or clear indication.

It will be seen, therefore, that a train moving through the track stretch in the normal direction causes the apparatus to operate to provide a two-block three-indication signal system with a full block overlap, while each train stop is caused to occupy its operative position as soon as the rear of the train passes beyond the location of the train stop.

If a second or following train approaches a signal, such as signal 12S at a time when the signal displays its stop indication and the arm of train stop 12V is in its operative position, the arm of the train stop may be caused to move to its inoperative position to permit the train to advance beyond this train stop. In order to effect this movement of the train stop, the train must be stopped, and the trainman depresses push button 12PB which has a normally open contact which when closed establishes the circuit including back contact 26 of relay 11TR, and wires 25 and 22 for supplying energy to the winding of the trip stop 12V. When the trip arm moves to its inoperative position contact 24 establishes a stick circuit to maintain the winding of the device energized after the push button is released.

Operation of apparatus on movement of a train through the track stretch in the reverse direction

For purposes of illustration it will be assumed that the track stretch is vacant and that it is desired to move a train through the stretch in the reverse direction, that is from right to left as viewed in the drawing. To permit such a train movement the operator moves lever K to its position R so that contact 32 interrupts the circuit of the red lamp R and establishes the circuit of the yellow lamp Y of signal 13SL. In addition, on this movement of lever K, contact 34 interrupts the circuit of relay 13H and establishes a pick-up circuit for relay 13D. This circuit includes front contact 26 of relay 13TR, and back contact 28 of relay 13H, while when relay 13D picks up its contact 27 establishes a stick circuit for the relay to maintain its contacts picked up after a train enters section 13T and contact 26 of track relay 13TR releases and interrupts the pick-up circuit for relay 13D.

At this time relay 13H is released and its contact 39 interrupts the circuit of the yellow lamp Y and establishes the circuit of the red lamp R of signal 13S, while contact 21 of relay 13H interrupts the circuit including front contact 20 of relay 13TR for supplying energy to the winding of trip stop 13V, and to the distant relay 12D. Accordingly, the trip-arm of the stop 13V moves to its upper or operative position and contact 24 interrupts the circuit of relay 12D, while on release of relay 12D signal 12S displays its yellow or caution indication.

When a train moving from right to left enters section 13T track relay 13TR releases and its contact 26 interrupts the pick-up circuit of relay 13D, but this relay is energized by current supplied over its stick circuit so its contact remain picked up so that energy is supplied over back contact 20 of track relay 13TR, front contact 35 of relay 13D, back contact 21 of relay 13H, and wire 22 to the winding of the trip stop 13V. Accordingly, the arm of the trip stop 13V moves to its lower or inoperative position to permit the train to pass over the trip, while contact 24 establishes connection from wire 22 to wire 25 so that energy is supplied over front contact 26 of

relay 12TR to relay 12D and its contacts pick up. At this time relay 12H is released because contact 37 of track relay 13TR is open so the trip stop 12V occupies its upper or operative position, and signal 12S displays its red or stop indication, while on picking up of relay 12D its contact 27 establishes a stick circuit for the relay including back contact 28 of relay 12H.

On release of relay 12H as a result of occupation of section 13T, contact 28 of relay 12H interrupts the supply of energy over wire 25 to relay 11D and relay 11D releases with the result that its contact 41 interrupts the circuit of the green lamp G and establishes the circuit of the yellow lamp Y of signal 11S.

When the train advances into section 12T track relay 12TR releases and contact 26 interrupts the pick-up circuit for relay 12D, but this relay is energized by current supplied over its stick circuit so its contacts remain picked up and establish the circuit for supplying energy to the winding of trip 12V and to relay 11D.

When the train vacates section 13T track relay 13TR picks up and its contact 29 interrupts the circuit including front contact 35 of relay 13D for supplying energy to the winding of trip stop 13V and the arm of this device moves to its upper or operative position.

Similarly, when the train vacates section 12T track relay 12TR picks up and its contact 20 interrupts the circuit including front contact 35 of relay 12D for supplying energy to the winding of trip stop 12V and the arm of this device moves to its upper or operative position unless the contacts of relay 12H pick up to establish a circuit for the winding of trip stop 12V.

The apparatus for section 11T is operated in response to the train moving in the reverse direction in the same manner as the apparatus for section 12T and a description of such operation need not be repeated.

From the foregoing it will be seen that the relay D for each section serves as a distant relay to select between the caution and clear signal indications of the associated signal on movement of a train through the track stretch in the normal direction, while on movement of a train through the track stretch in the reverse direction the relays D serve as directional stick relays and are progressively controlled by the track relays to cause the train stops to be progressively moved to inoperative positions and thus permit a train to pass over the train stops. The relays D are released behind the train moving in the reverse direction so that control of the train stops is restored to the track and home relays.

The equipment is arranged so that on movement of a train through the track stretch in the reverse direction the train stop for each section is energized as soon as the train enters the associated section. Accordingly, each train stop will have ample time to complete its movement to the inoperative position before the train passes through the track section and reaches the train stop.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of railway track

having a normal direction of traffic and formed with consecutive track sections each of which is provided with a track circuit including a track relay, a trackway train control device for each section for use with cooperating train carried apparatus and capable of assuming an inoperative or an operative position according as an associated control circuit is closed or open, a home relay for each section which is picked up when and only when the associated section and the adjacent section in advance are vacant, a distant relay for each section, a signal for each section governed by the associated home and distant relays, means including front contacts of the track and home relays of a track section for closing the circuit of the control device for such section, means including back contacts of the track and home relays and a front contact of the distant relay for a track section for also closing the circuit of the control device for such section, a pick-up circuit for the distant relay for each section including a front contact of the track relay of the associated section and a contact closed when and only when the control device for the section in advance is in its inoperative position, and a stick circuit for each distant relay including its own front contact and a back contact of the associated home relay.

2. In combination, a stretch of railway track having a normal direction of traffic and formed with consecutive track sections each of which is provided with a track circuit including a track relay, a trackway train control device for each section for use with cooperating train carried apparatus and capable of assuming an inoperative or an operative position according as an associated control circuit is closed or open, a home relay for each section which is picked up when and only when the associated section and the adjacent section in advance are vacant, a distant relay for each section, a signal for each section governed by the associated home and distant relays, means including a front contact of the home relay for a track section for closing the circuit of the control device for such section, means including back contacts of the track and home relays and a front contact of the distant relay for a track section for also closing the circuit of the control device for such section, a pick-up circuit for the distant relay for each section including a front contact of the track relay of the associated section and a contact closed when the control device for the section in advance is in its inoperative position, and a stick circuit for each distant relay including its own front contact and a back contact of the associated home relay.

3. In combination, a stretch of railway track having a normal direction of traffic and formed with consecutive track sections each of which is provided with a track circuit including a track relay, a trackway train control device for each section for use with cooperating train carried apparatus and capable of assuming an inoperative or an operative position according as an associated control circuit is closed or open, a home relay for each section which is picked up when and only when the associated section and the adjacent section in advance are vacant, a distant relay for each section, a signal for each section governed by the associated home and distant relays, means including a front contact of the home relay for a track section for closing the circuit of the control device for such section, means including a back contact of the track relay

and a front contact of the distant relay for a track section for also closing the circuit of the control device for such section, a pick-up circuit for the distant relay for each section including a front contact of the track relay of the associated section and a contact closed when the control device for the section in advance is in its inoperative position, and a stick circuit for each distant relay including its own front contact and a back contact of the associated home relay.

4. In combination, a stretch of railway track having a normal direction of traffic and formed with consecutive track sections each of which is provided with a track circuit including a track relay, a trackway train control device for each section for use with cooperating train carried apparatus and capable of assuming an inoperative or an operative position according as an associated control circuit is closed or open, a home relay for each section which is picked up when and only when the associated section and the adjacent section in advance are vacant, a distant relay for each section, a signal for each section governed by the associated home and distant relays, means including a front contact of the home relay for a track section for closing the circuit of the control device for such section, means including a front contact of the distant relay for a track section for also closing the circuit of the control device for such section, a first pickup circuit for each distant relay including a contact closed only when the associated track section is vacant and a front contact of the home relay for the adjacent track section in advance, a second pick-up circuit for each distant relay including front contacts of the track relay for the associated track section and of the distant relay for the adjacent section in advance and a back contact of the track relay for the adjacent section in advance, and a stick circuit for each distant relay including its own front contact and a back contact of the associated home relay.

5. In combination, a stretch of railway track having a normal direction of traffic and formed with consecutive track sections each of which is provided with a track circuit including a track relay, a trackway train control device for each section for use with cooperating train carried apparatus, each control device having an arm biased to an operative position and being moved to an inoperative position when a winding associated with the device is energized, a home relay for each section which is picked up when and only when the associated section and the adjacent section in advance are vacant, a distant relay for each section, a signal for each section governed by the associated home and distant relays, a line wire for each section substantially coextensive with the section, a circuit including a front contact of the home relay for each section for supplying energy to the winding of the associated control device and if the arm of said control device is in its inoperative position and the track relay for the adjacent section in the rear is picked up to also supply energy over the line wire for the section in the rear to the distant relay for the section in the rear, a circuit including a front contact of the distant relay and a back contact of the track relay for each section for supplying energy to the winding of the associated control device and if the arm of said control device is in its inoperative position and the track relay for the section in the rear is picked up to also supply energy over the line wire for the section in the rear to the distant relay for the section in the

rear, a stick circuit for each distant relay including its own front contact and a back contact of the associated home relay, and for each control device a circuit for supplying energy to the winding thereof over the line wire for the adjacent section in the rear provided the track relay for said section in the rear is released and the arm of said control device is in its inoperative position.

6. In combination, a stretch of railway track having a normal direction of traffic and divided into a forward, an intermediate and a rearward track section each of which is provided with a track circuit including a track relay, a trackway train control device for said intermediate section having an arm biased to an operative position and being moved to an inoperative position when a winding associated with the device is energized, a contact governed by said control device and closed when the arm of said device is in its inoperative position, a home relay which is energized only when the track relays for the intermediate and forward sections are picked up, a distant relay for the intermediate section, a signal for said intermediate section controlled by said home and distant relays, a control relay for the forward section, means for energizing said control relay to establish traffic over the track stretch reverse to said normal direction, means controlled by said control relay and by the track relay of the forward section for energizing the distant relay when said forward section is vacant or is occupied by a train moving in the reverse direction, means controlled by the home and distant relays for the intermediate section for energizing said distant relay when either the intermediate or the forward section is occupied by a train moving in the reverse direction, and three circuits for energizing the winding of said control device, one of said circuits including a front contact of said home relay for said intermediate section, the second of said circuits including a front contact of said distant relay, and the third of said circuits including said control device contact and a back contact of the track relay for said rearward section.

7. In combination, a stretch of railway track having a normal direction of traffic and divided into a forward and a rearward track section each of which is provided with a track circuit including a track relay, a trackway train control device for said rearward section having an arm biased to an operative position and being moved to an inoperative position when a winding associated with the device is energized, a home relay which is energized only when the track relays for the rearward and forward sections are picked up, a distant relay for said rearward section, a signal for said rearward section governed by said home and distant relays, a control relay for the forward section, means for energizing said control relay to establish traffic over the track stretch reverse to said normal direction, means controlled by said control relay and by the track relay of said forward section for energizing said distant relay when said forward section is vacant or is occupied by a train moving in the reverse direction, a circuit including a front contact of said distant relay and a back contact of said home relay for energizing said distant relay, a circuit including a front contact of said home relay for energizing the winding of said control device, and a circuit including a front contact of said distant relay for also energizing the winding of said control device.

8. In combination, a stretch of railway track

having a normal direction of traffic and divided into a forward and a rearward section each of which is provided with a track circuit including a track relay, a trackway train control device for said rearward section having an arm biased to an operative position and being moved to an inoperative position when a winding associated with the device is energized, a home relay for the rearward section which is energized only when the track relays for the rearward and forward sections are picked up, a distant relay for said rearward section, a signal for said rearward section governed by said home and distant relays, a first and a second control relay for the forward section, a circuit including a front contact of the forward section track relay for energizing said first control relay, means for interrupting the circuit of the first control relay and establishing a circuit for said second control relay, a signal for said forward section governed by said first control relay, a circuit including a front contact of said first control relay for supplying energy to said distant relay, a circuit including a front contact of said second control relay for supplying energy to said distant relay, a circuit including a front contact of said distant relay and a back contact of said home relay for supplying energy to said distant relay, a circuit including a front contact of said home relay for energizing the winding of said control device, and a circuit including a front contact of said distant relay for energizing said control device.

9. In combination, a stretch of railway track having a normal direction of traffic and formed with consecutive track sections each of which is provided with a track circuit including a track relay, a trackway train control device for each section for use with cooperating train carried control apparatus and capable of assuming an inoperative or an operative condition according as an associated control circuit is closed or opened, a home and a distant relay for each section, a signal for each section governed by the associated home and distant relays, means for each control device including a front contact of the associated home relay for closing the circuit of said control device, means for each control device including a front contact of the associated distant relay and a back contact of the associated track relay for also closing the circuit of said control device, an energizing circuit for each home relay including front contacts of the associated track relay and of the track relay for the adjacent section in advance, circuit means governed by said track relays when a train traverses said track stretch in the normal direction to energize each of said distant relays when and only when the track relay of the associated section and the home relay of the adjacent section in advance are picked up, and circuit means governed by said track relays when a train traverses said track stretch in the reverse direction to energize each of said distant relays when the associated section is occupied.

10. In combination, a stretch of railway track having a normal direction of traffic and formed with consecutive track sections each of which is provided with a track circuit including a track relay, a trackway train control device for each section for use with cooperating train carried control apparatus and capable of assuming an inoperative or an operative condition according as an associated control circuit is closed or opened, a home and a distant relay for each section, a signal for each section governed by the associ-

ated home and distant relays, means for each control device including a front contact of the associated home relay for closing the circuit of said control device, means for each control device

- 5 including a front contact of the associated distant relay and a back contact of the associated track relay for also closing the circuit of said control device, an energizing circuit for each home relay including front contacts of the associated
- 10 track relay and of the track relay for the adjacent section in advance, circuit means governed by said track relays when a train traverses said track stretch in the normal direction to energize each of said distant relays when and only when the track relay of the associated section and the home relay of the adjacent section in advance are picked up, and circuit means governed by said track relays when a train traverses said track stretch in the reverse direction to energize each of said distant relays when the associated section or the adjacent section in advance is occupied.

11. In combination, a stretch of railway track having a normal direction of traffic and formed with consecutive track sections each of which is provided with a track circuit including a track relay, a trackway train control device for each section for use with cooperating train carried apparatus and capable of assuming an inoperative or an operative position according as an associated control circuit is closed or open, a home relay for each section which is picked up when and only when the associated section and the adjacent section in advance are vacant, a distant relay for each section, a signal for each section governed by the associated home and distant relays, means including a front contact of the home relay for a track section for closing the circuit of the control device for such section, means including a front contact of the distant relay for a track section for also closing the circuit of the control device for such section, a first pick-up circuit for each distant relay including a contact closed only when the associated track section is vacant and a front contact of the home relay for the adjacent track section in advance, a second pick-up circuit for each distant relay including front contacts of the track relay for the associated track section and of the distant relay for the adjacent section in advance, and a stick circuit for each distant relay including its own front contact and a back contact of the associated home relay.

12. In combination, a stretch of railway track having a normal direction of traffic and formed with consecutive track sections each of which is provided with a track circuit including a track relay, a trackway train control device for each section for use with cooperating train carried apparatus and capable of assuming an inoperative or an operative position according as an associated control circuit is closed or open, a home relay for each section which is picked up when and only when the associated section and the adjacent section in advance are vacant, a distant relay for each section, a signal for each section governed by the associated home and distant relays, means including a front contact of the home relay for a track section for closing the circuit of the control device for such section, means including a front contact of the distant relay for a track section for also closing the circuit of the control device for such section, a pick-up circuit for the distant relay for each section including a contact closed only when the as-

sociated section is vacant and a contact closed when the control device for the section in advance is in its inoperative position, and a stick circuit for each distant relay including its own front contact and a back contact of the associated home relay.

13. In combination, a stretch of railway track having a normal direction of traffic and formed with consecutive track sections each of which is provided with a track circuit including a track relay, a trackway train control device for each section for use with cooperating train carried control apparatus and capable of assuming an inoperative or an operative condition according as an associated control circuit is closed or opened, a home and a distant relay for each section, a signal for each section governed by the associated home and distant relays, means for each control device including a front contact of the associated home relay for closing the circuit of said control device, means for each control device including a front contact of the associated distant relay for also closing the circuit of said control device, an energizing circuit for each home relay including front contacts of the associated track relay and of the track relay for the adjacent section in advance, circuit means governed by said track relays when a train traverses said track stretch in the normal direction to energize each of said distant relays when and only when the track relay of the associated section and the home relay of the adjacent section in advance are picked up, and circuit means governed by said track relays when a train traverses said track stretch in the reverse direction to energize each of said distant relays when the associated section is occupied.

14. In combination, a stretch of railway track having a normal direction of traffic and formed with consecutive track sections each of which is provided with a track circuit including a track relay, a trackway train control device for each section for use with cooperating train carried control apparatus and capable of assuming an inoperative or an operative condition according as an associated control circuit is closed or opened, a home and a distant relay for each section, a signal for each section governed by the associated home and distant relays, means for each control device including a front contact of the associated home relay for closing the circuit of said control device, means for each control device including a front contact of the associated distant relay for also closing the circuit of said control device, an energizing circuit for each home relay including front contacts of the as-

sociated track relay and of the track relay for the adjacent section in advance, circuit means governed by said track relays when a train traverses said track stretch in the normal direction to energize each of said distant relays when and only when the track relay of the associated section and the home relay of the adjacent section in advance are picked up, and circuit means governed by said track relays when a train traverses said track stretch in the reverse direction to energize each of said distant relays when the associated section or the adjacent section in advance is occupied.

15. In combination, a stretch of railway track having a normal direction of traffic and formed with consecutive track sections each of which is provided with a track circuit including a track relay, a trackway train control device for each section for use with cooperating train carried apparatus, each control device having an arm biased to an operative position and being moved to an inoperative position when a winding associated with the device is energized, a home relay for each section which is picked up when and only when the associated section and the adjacent section in advance are vacant, a distant relay for each section, a signal for each section governed by the associated home and distant relays, a line wire for each section substantially coextensive with the section, a circuit including a front contact of the home relay for each section for supplying energy to the winding of the associated control device and if the arm of said control device is in its inoperative position and the track relay for the adjacent section in the rear is picked up to also supply energy over the line wire for the section in the rear to the distant relay for the section in the rear, a circuit including a front contact of the distant relay for each section for supplying energy to the winding of the associated control device and if the arm of said control device is in its inoperative position and the track relay for the section in the rear is picked up to also supply energy over the line wire for the section in the rear to the distant relay for the section in the rear, a stick circuit for each distant relay including its own front contact and a back contact of the associated home relay, and for each control device a circuit for supplying energy to the winding thereof over the line wire for the adjacent section in the rear provided the track relay for said section in the rear is released and the arm of said control device is in its inoperative position.

55 ARTHUR L. JEROME.
